UNITED STATES PATENT OFFICE.

WILLIAM O'CONNELL, OF DETROIT, MICHIGAN.

DREDGING APPARATUS.

1,307,370.

Specification of Letters Patent. Patented June 24, 1919.

Application filed November 13, 1918. Serial No. 262,398.

To all whom it may concern:

Be it known that I, WILLIAM O'CONNELL, a citizen of the United States, residing at Detroit, in the county of Wayne and State 5 of Michigan, have invented certain new and useful Improvements in Dredging Apparatus, of which the following is a full, clear, and exact description, reference being had to the accompanying drawings, forming a 10 part hereof.

The present invention is directed to improvements in dredging apparatus, being particularly designed for application in connection with the dredging of the bottoms of 15 rivers, lakes, harbors, marshes and similar bodies of water with a view of deepening the same. The main object sought is to construct a dredger whereby the dredging operation may be made continuous, the mud as fast 20 as it is scooped up from the bottom of the river or other body of water being immediately delivered to a chute or trough which conducts it to a scow or boat to be hauled away to any point along the bank or otherwise 25 disposed of. A further object is to construct a dredger which shall be under ready control of the engineer, one which is simple in design, strong and rigid, and one possessing further and other advantages better 30 apparent from the following detailed description in connection with the accompanying drawings in which—

Figure 1 represents a side elevation of the bucket conveyer, the boat nearest the object 35 server having been removed, a part of the superstructure and mud chute being in section; Fig. 2 is a front elevation of the dredger; Fig. 3 is a top plan of the oscillating lever frame and bucket conveyer, the opposite 40 site ends of the conveyer being removed to better expose the frame; Fig. 4 is a vertical longitudinal section on the line 4—4 of Fig. 3; Fig. 5 is a bottom end view of the lever frame; Fig. 6 is a vertical sectional detail 45 on the line 6—6 of Fig. 2; Fig. 7 is an enlarged detail plan of a portion of the bucket conveyer, parts being in section; Fig. 8 is a longitudinal sectional detail on the line 8—8 of Fig. 7; and Fig. 9 is a diagrammatic plan 50 view of the apparatus.

Referring to the drawings, 1, 1, represent two boats disposed parallel to one another and spaced apart, and connected rigidly to one another at one end by a housing or superstructure 2 serving as an engine house, 55 the engine E being indicated conventionally

in Fig. 1 of the drawings. The members 1, 1, and 2, form a rigid U-shaped float, the arms or members 1, 1, of which are separated by a working space *a* in which is free to oscillate in a vertical plane the lever frame 3 which may be constructed in any suitable mechanical manner, and here shown as made up of longitudinal and transverse structural members suitably braced, a construction well 60 within the purview of any skilled mechanic. This frame is divided into a long and short lever arm by the axis of the drive-shaft 4 spanning the space *a* between the boats and supported in bearings 5, 5, on the decks of 65 the boats. One end of the shaft extends a suitable distance beyond its bearing 5, said end being provided with a pulley 6 from which leads a drive belt 7 to the pulley 8 of the engine shaft, a suitable opening *o* in the 70 front wall of the engine room 3 allowing for the free passage of the upper lap of the belt, the lower lap traveling in a groove *h* in the deck of the boat 1. Hinged near the free end of the long arm of the lever frame 3 is a yoke 75 9 the cross member of which is provided with an eye-bolt 10 to which is coupled a link 11, the latter being connected to the hoisting tackle *t* of conventional design secured to the float in any suitable mechanical manner, 80 there being disposed on each boat 1 a mast 12 and boom 13 as an adjunct to the tackle *t*, said mast and boom forming a derrick or rigging for the hoisting tackle *t'* which when in service is coupled to the strap or 85 bail 14 carried by the lower trough section 15 leading from the upper section 15' into which the material is directly discharged from the dredger buckets presently to be described. When not in service the tackle *t'* 90 is anchored to an eye or ring *w* on the deck of the boat 1. In the present embodiment of my invention the sides of the trough section 15 terminate at one end in inwardly folded lips 16 which embrace more or less 95 loosely the sides of the adjacent shallow portion 15'' of the trough section 15', the portion 15'' overlapping the section 15 as clearly shown in Fig. 2, the resulting telescopic connection between the sections 15, 100 15', permitting extension or contraction of the sections should it become necessary to lengthen or shorten the trough as a whole. The trough 15, 15', should be sufficiently 105 pitched to conduct away the wet mud, a scow S being here shown in dotted outline adjacent the dredger to receive the material dis-

charged from the trough. Should it be desirable to change the pitch of the trough, this may be done by lifting or lowering (it is in its lowest position in Fig. 2) the same by means of the tackle t' as clearly obvious from the drawings. In practice the trough merely rests on suitable brackets d , d , projecting forwardly beyond the free ends of the boats 1, 1, and preferably secured to the 10 inner adjacent sides of the boats.

In the present embodiment of my invention I make use of an endless conveyer equipped with buckets, the latter scooping up the mud from the bottom of the water body and discharging it into the trough 15, 15', above referred to. The conveyer herein comprises a series of rods 17 disposed across the lever frame, the several rods being connected at the ends and on either side of the 15 longitudinal center of the frame 3 by links 18, suitable spacing tubes or thimbles 19 being disposed between and outside the links to maintain the links against displacement, the arrangement being substantially as 20 shown in Figs. 7 and 8. Disposed at intervals between two successive rods 17 on opposite sides of the medial longitudinal line of the conveyer are the dredging buckets 20 substantially V-shaped in cross-section, the 25 ridge of a bucket being pivotally coupled to a sleeve 19 by straps or hinges 21 wrapped about the sleeve (Fig. 8), the inner wall of the bucket or that opposite the cutting wall being provided at the opposite ends of its 30 free edge with straps or clips 22 which are looped around the sleeve of the next succeeding conveyer rod, the last mentioned rod having secured thereto one end of an apron 23 the opposite end of the apron being coupled to the sleeve 19 of the third rod. As 35 shown to best advantage in Figs. 7 and 8, the apron is recessed at the corners on the side facing the bucket to make room for the clips 22, the end of the apron between said 40 recessed portions being wrapped about the sleeve 19 of the adjacent rod in one direction, while the opposite end of the apron or that farthest from the bucket is wrapped about the sleeve 19 of its rod in the opposite 45 direction. The arrangement described results in a flexible bucket conveyer there being no binding between the several parts as the conveyer travels around the lever frame 3. The buckets and their aprons do not follow each other continuously or without an 50 interruption or gap in the series, but are so arranged that the buckets (and their aprons) on one side of the medial longitudinal line of the conveyer are in staggered relation with those on the other side of said medial line, thereby bringing a bucket and apron on one side adjacent to an open space on the opposite side as fully shown in Fig. 55 3. The result of this arrangement is that 60 the buckets discharge successively on oppo-

site sides of the medial line of the conveyer, one bucket discharging on one side, and the next bucket discharging on the opposite side of said line, thereby preventing congestion of the material discharged into the trough 70 15, 15', and facilitating the delivery of the material from the trough into the scow S.

The bucket conveyer is actuated by the following mechanism: Terminating the upper end of the lever frame 3 is a shaft 24 75 on which are disposed three sprocket disks 25 provided with suitable peripheral depressions to engage the rods 17 (or rather the sleeves 19 by which they are covered) there being disposed at the opposite end of the 80 frame a parallel tail shaft 24' with corresponding sprocket disks 25' for engaging the rods of the conveyer. The opposite ends of the shaft 24 are provided with sprocket wheels 26 driven by chains 27 which pass 85 over the sprocket pinions 28 on the drive-shaft 4 which as we have already seen has rotation imparted thereto from the belt 7. Rotation being imparted to the shaft 24 in the direction indicated by the arrows in Fig. 90 1, and the lever frame 3 being lowered sufficiently to bring the buckets 20 into engagement with the mud m at the bottom of the river the level of which is indicated by the line α (Fig. 1), it follows that the 95 buckets on opposite sides of the medial longitudinal line of the conveyer will alternately scoop up the mud, carrying it upward to the raised end of the lever frame and as the buckets pass over the top of the 100 frame they will discharge their contents into the trough 15, 15', which conducts it to the scow S. The buckets then pass along the lower lap of the conveyer to repeat the operation. Features shown but not alluded to 105 are well-known in the art and require neither reference nor description in the present connection. It is of course apparent that the structure is susceptible of many changes which will fall within the purview of the 110 skilled mechanic, but which would not take the resulting structure out of the sphere of the present invention.

Having described my invention what I claim is:

115

1. In a dredging apparatus of the character described, a chain bucket-conveyer comprising a series of transverse parallel rods, links disposed in pairs connecting said rods, spacing sleeves on the rods disposed between the links, an apron having terminals looped about two successive sleeves, a bucket disposed in adjacent relation to an apron along the conveyer, the bucket being provided with loops hinged about the sleeve supporting one end of an apron and the next succeeding sleeve, the conveyer having a series of buckets and associated aprons disposed on one side of a longitudinal medial line of the conveyer and spaced apart and a corre- 130 125 120 110 105 100 95 90 85 80 75 70 65 60 55 50 45 40 35 30 25 20 15 10 5

sponding series of buckets and conveyers on the opposite side of said line and spaced apart, a bucket and apron on one side alternating with a bucket and apron on the opposite side, whereby a bucket and apron on one side of the conveyer comes opposite a space on the opposite side, the buckets discharging in succession first on one side and then the other of the medial longitudinal line 10 of the conveyer.

2. In a dredging apparatus of the character described, an endless conveyer comprising a series of aprons and associated buckets disposed on one side of a longitudinal medial line of the conveyer and spaced apart, and a corresponding series of aprons

and associated buckets on the opposite side of said medial line and spaced apart, a bucket and apron on one side alternating with a bucket and apron on the opposite side, whereby a bucket and apron on one side of the conveyer comes opposite a space on the opposite side, the buckets discharging in succession first on one side and then on the other of the longitudinal medial line 20 25 aforesaid.

In testimony whereof I affix my signature, in presence of two witnesses.

WILLIAM O'CONNELL.
